UNITED STATES PATENT OFFICE.

RALPH P. HAWLEY, OF MONONGAHELA, PENNSYLVANIA.

HINGE.

No. 898,360.

Specification of Letters Patent.

Patented Sept. 8, 1908.

Application filed November 25, 1907. Serial No. 403,680.

To all whom it may concern:

Be it known that I, RALPH P. HAWLEY, a citizen of the United States, and a resident of Monongahela city, in the county of Washington and State of Pennsylvania, have invented a new and Improved Hinge, of which the following is a full, clear, and exact description.

This invention is an improvement in hinges, relating more especially to hinges for waffle-irons and other devices in which it is unnecessary to separate or revolve the hinge members on each other as much as 180° , usually no appreciable distance over 90° .

The object of the invention primarily is to provide a hinge in which the members thereof are rigid with their respective pivots, and may be separated or lifted apart when the hinge is open.

Reference is to be had to the accompanying drawings forming a part of this specification, in which similar characters of reference indicate corresponding parts in all the views.

Figure 1 is a perspective view of a hinge embodying my invention as applied to a waffle-iron; Fig. 2 is a cross-section on the line 2—2 of Fig. 4, looking in the direction of the arrow; Fig. 3 is an inner face view of one of the hinge members; and Fig. 4 is a side elevation of the hinge, showing the base of the waffle-iron in section, and one of the hinge members in a dotted position as when fully open.

I have shown for convenience my improved hinge in connection with a waffle-iron, the latter comprising the cylindrical base 5, in the upper edge of which are provided notches, in which are revolvably mounted the trunnions, one-half of each being formed on each section 6 of the iron, the said sections having the usual handles provided with the oppositely-disposed grips 7. The trunnion of the iron embodying the hinge of the two iron sections, and which is the principal feature of my invention, is composed of two separable hinge members 8, 8, of like construction, each hinge member having in the present instance semi-cylindrical shanks placed together to provide the trunnion for the iron, and is cut out on a central vertical plane at one side to provide a shoulder 9. In the angles between the shoulders 9 and the flat faces of the shanks of the hinge members, the members are provided with rounded alining pivots 10, integral or otherwise rigid with their respective hinge members, the pivots being

arranged on a median line of the hinge, each fitting into a corresponding groove formed in the opposed hinge member. The hinge members are constructed at the opposite side or outside of the pivots 10, with extensions 11, which, in the position of the hinge as shown, are off-set in a vertical plane to bring their under faces in a longitudinal central plane of the hinge and in contact when the hinge is closed, thus preventing the hinge members from being lifted apart or separated when in closed position, but making them readily separable when one of the members is revolved to the dotted position illustrated in Fig. 4.

As is best observed in Fig. 3, the extensions 11 of the hinge members are also laterally off-set to provide the pointed or substantially wedge-shaped projections 12, which are adapted to be alternately engaged, when the sections of the waffle-iron are separated, in a notch 13 formed exteriorly of and in a thickened portion of the cylindrical base 5. This engagement prevents the waffle-iron from revolving on its trunnions when the sections of the iron are open.

The shoulders 9 of the hinge members are made to conform to the outer faces of the extensions 11, whereby a substantial seating surface is provided when the hinge members are fully separated, and in which position said members may be readily lifted apart.

While I have shown my improved hinge in connection with a waffle-iron in order that one of its many applications might be fully understood, I nevertheless recognize that the hinge will be found valuable in many other relations, and consider that I am entitled to such modifications as fall within the scope of the claims annexed.

Having thus described my invention, I claim as new and desire to secure by Letters Patent:

1. The combination of a cylindrical base, and hinge members having semi-cylindrical shanks placed together and revolvably mounted in the base, each hinge member having a rounded pivot rigid therewith and fitting in a corresponding groove in the opposed hinge member, and provided with a laterally off-set extension, one of said extensions being adapted to engage with a notch in the base and prevent rotation of the shanks thereon, and the other provide a seat for the opposite hinge member when the hinge members are separated on their pivots.

2. A hinge comprising two separable hinge members having pivots, each pivot being rigid with its respective member and fitting into a groove in the opposed member, said members having contacting faces at each side of the pivots and arranged at the opposite sides of the longitudinal center of the hinge, whereby the members cannot be bodily separated when the hinge is closed.
- 5 3. A hinge comprising two separable members each having a pivot rigid therewith fitting in a groove in the opposed member, said members having oppositely-arranged faces movable into contact at both sides of the pivot when the hinge is closed.
- 10 4. A hinge, comprising two members having alining pivots, each pivot being rigid with its respective member, each of the members being cut out at one side at substantially 15 right-angles to its pivot to provide a shoul-
- der, and an extension rigid with each member, adapted to contact when the hinge is closed and providing a seat for the shoulder of the opposite hinge member when the hinge is open.
- 25 5. A hinge comprising two separable members of like construction, each member having a pivot rigid therewith fitting into a groove in the opposed member and provided with an extension adapted to contact 30 with the extension of the other member and prevent the separation of said members when the hinge is closed.
- 35 In testimony whereof I have signed my name to this specification in the presence of two subscribing witnesses.

RALPH P. HAWLEY.
